CARTONS FROM MUTUALLY NESTABLE BLANKS

Kenneth T. Buttery and Norman A. Nuyen, Kalamazoo, Mich., assignors, by mesne assignments, to Brown Company, a corporation of Delaware

Filed June 16, 1965, Ser. No. 464,455
5 Claims. (Cl. 229—51)

The present invention relates to cartons, and is more particularly concerned with cartons which may be readily and inexpensively erected from integral cut and scored mutually nestable blanks, and which cartons may be readily and positively sealed by means of automatic machinery.

Cartons having a so-called "flip-top" cover hingedly connected to the edge of the rear panel, which may be erected with the cover in sealed condition and which may be readily opened by the removal of a tear strip, have become exceedingly popular, particularly as containers for food items such as ice cream. Once the tear strip is removed, the cover may be opened for access to some or all of the contents, and may be reclosed for further storage until the contents have been completely consumed. Cartons of the type described which have been available in the prior art, although satisfactory in use, have the disadvantage that they are difficult to construct and seal on automatic machinery.

Prior art cartons are generally provided with an outer front wall member integral with the cover of the carton, having its own flaps extending at the ends thereof. A tear strip is provided as an integral unit and extends from the end of one outer front wall flap, across the outer front wall, and to the end of the opposite outer front wall flap. Such a structure is expensive, difficult to construct into a carton from an integral blank, and requires expensive machinery for the purposes of erection and sealing. Additionally, such cartons require a greater amount of paperboard, thus adding to the material cost. For many purposes it is sufficient for only the cover front wall to be provided with detachable means adhesively affixing the cover to the front wall of the carton. Even where it is necessary for the cover end wall panels to be affixed, for most purposes affixing the panels at limited zones is sufficient.

Prior art cartons also have the disadvantage that, in order to heat-seal the outer end flaps to inner end flaps, it is often necessary for the heat to travel through the thickness of an intermediate flap, often resulting in improper sealing. Still a further disadvantage in prior art cartons is that, where it is not convenient to seal the outer end flaps along their entire height, the end structure is somewhat weakened and the outer flaps at their unsealed edges have a tendency to curl outwardly, detracting from the appearance of the carton and additionally permitting the curled edges to catch on objects with which they come in contact and to become torn, disfigured, or discolored. A further addition to material cost of prior art cartons results from the fact that they must be cut from a substantially rectangular blank. Consequently, there is no opportunity to nest adjacent blanks with each other to provide a saving in material cost.

It is an object of the present invention to provide cartons which may be formed from integral cut and scored mutually nestable blanks. It is a further object to provide a top-opening carton which may be sealed by means of a detachable adhesive strip affixing the cover to the front wall of the carton. It is another object to provide such a carton which may be readily reclosed when it is desired to store unconsumed contents. It is a still further object to provide a carton of the type described which can be readily erected and subsequently sealed by means of relatively simple and inexpensive

machinery. It is an additional object to provide a carton having its panels so contoured to facilitate assembling and heat sealing the various panels to form a strongly sealed carton. It is still an additional object to provide

- 5 a carton the end panels of which may be heat-sealed with greater facility than those cartons of the art where heat must travel through an intermediate flap in order to complete the sealing of the end flaps. It is still a further object to provide means whereby the end panels of the 10 carton cover may be affixed to the junction of the outer end flaps, thus serving a supplemental function in securing the outer end flaps together in addition to securing the cover end panels to the carton ends. The accomplishment of the foregoing and additional objects will 15 become more fully apparent hereinafter.

The invention in its preferred embodiment is illustrated by the accompanying drawings in which:

FIG. 1 is a plan view of a blank cut and scored for assembling a carton according to the invention, additionally showing a portion of an adjacent nesting blank.

FIG. 2 is a plan view of the blank folded over and glued to form a flattened tube.

FIG. 3 is an end view of the carton with several of the flaps folded into position.

25 FIG. 4 is a perspective view of the sealed carton; and

FIG. 5 is a perspective view of the carton of FIG. 4 after the seal has been broken and the cover opened.

According to the invention, a carton is provided having panels including a bottom member having a pair of inner end wall flaps hingedly connected to the ends thereof of a front wall member hingedly connected to an edge of the bottom member having front wall outer end flaps hingedly connected to the ends thereof, and a rear wall member hingedly connected to the other edge of the 30 bottom member having rear wall outer end flaps hingedly connected to the ends thereof. The rear wall outer end flaps, the cover end wall flaps, and the cover front wall end flaps are designed to be shorter than the front wall outer end flaps or the inner end wall flaps. Additionally, 35 the upper terminal corner of each rear wall outer end flap is provided with a rectangular recess or cut-out so designed that when adjacent blanks are nested together in opposite directions with the rear wall outer end flaps in edge-to-edge engagement, the edges of the rear upper corner of the inner end wall flap of one blank are nested in edge-to-edge engagement with the edges of the upper terminal corner recess of the rear wall outer end flap of the other blank. In a preferred embodiment, the lower 40 terminal corners of the rear wall outer end flap are also provided with a preferably rectangular recess or cut-out having its vertical edge substantially colinear with that of the upper terminal corner recess. The front wall outer end flaps are dimensioned so that they may be folded over and affixed to the rear wall outer end flaps with 45 their terminal edges substantially in engagement with the vertical or rear edges of both recesses. The lower corner of the front wall outer end flap may be directly adhesively affixed to the inner end wall flap through the lower terminal recess of the rear wall outer end flap 50 where such structure is utilized. A cover is also provided which is hingedly connected to the upper edge of the rear wall member. The cover is provided with cover flaps comprising cover end wall panels and a cover front wall panel. Detachable means, as for example an adhesive strip, is affixed to the edge of the cover front wall panel at a severance line or by a tear strip, adhesively affixing the cover front wall panel to the front wall member. Additionally, the cover end wall panels are each provided with a detachable adhesive panel connected thereto at a severance line. When the carton is 55 sealed, the adhesive panel is affixed to both the front wall outer end flap and the rear wall outer end flap at the

- 55 connected thereto at a severance line. When the carton is sealed, the adhesive panel is affixed to both the front wall outer end flap and the rear wall outer end flap at the 60 65 70

line of engagement between the upper portion of the terminal edge of the front wall outer end flap and the vertical edge of the recess of the rear wall outer end flap. As a result, the adhesive panel serves the dual function of securing the cover end wall panels to the end portion of the carton proper, and additionally securing the upper edges of the front wall outer end flap and rear wall outer end flap together to form a strong sealed carton.

Reference is now made to the accompanying drawings for a better understanding of the invention, wherein all of the parts are numbered, wherein the same numbers are used to refer to corresponding parts throughout, and wherein areas having an adhesive applied thereto are indicated by stippled shading. In a preferred form, the carton of the invention is constructed from an integral blank, as illustrated in FIG. 1, and comprises a bottom panel member 1, a front wall member 2, and a rear wall member 3 hingedly connected to the bottom member 1. A cover 4 is hingedly connected to the rear wall member 3. The bottom 1 is provided at its end with inner end wall flaps 5 hingedly connected thereto, the front wall member 2 is provided at its ends with front wall outer end flaps 6 hingedly connected thereto, and the rear wall member 3 is provided with rear wall outer end flaps 7 hingedly connected thereto.

The cover 4 is provided with end flaps 8 comprising cover end wall panels 9 and adhesive panels 10 connected to the panels 9 at severance or fracture lines 11. As shown, the lower edges of the adhesive panels 10 extend below the edges of the cover end wall panels 9. However, the adhesive panels may be designed, if desired, so that their lower edges are flush with, or even recede from, the line defined by the edges of the cover end wall panel 9. The cover 4 is provided at its forward edge with a cover flap 12 comprising a cover front wall panel 13, parallel severance or fracture lines 14 defining a tear strip 15 having a tab 16 at one end thereof and detachably connecting the cover front wall panel 13 to an adhesive strip 17 affixed to the front wall member 2. The cover front wall panel 13 is also provided at its ends with end flaps 18 for being adhesively affixed to the cover end wall panels. The flaps 7 and 18 at the ends of the rear wall member and cover are so designed that they are shorter than the end flaps 5 and 6 of the bottom 1 and front wall panel 2. Additionally, rear wall outer end flap 7 is provided with an upper terminal corner recess 20 of substantially rectangular contour. Consequently, adjacent blanks may be arranged in opposite directions and may be nested together with the edges of the rear upper corner of the inner end wall flap 5 of one blank in edge-to-edge engagement with the edges of the upper terminal corner recess 20 of the rear wall outer end flap 7 of the other blank, as shown in FIG. 1.

The rear wall outer end flaps 7 are also provided with lower terminal corner recesses 19 in the preferred embodiment shown. As a consequence, when the front wall outer end flaps 6 are folded thereover, they may be adhesively affixed directly to the inner end wall flap 5 through the recess 19.

In assembling the carton, the carton blank may be folded at the score line between the bottom 1 and the rear wall member 3. The cover front wall panel 13 is then folded over and the adhesive strip 17 affixed to the outer surface of the front wall member 2, forming a folded tube, as shown in FIG. 2. Alternatively, the front wall member 2 may be folded over at the score line connecting it with the bottom 1, and the adhesive strip 17 may then be glued to the outer surface of the front wall member 2 in the same manner. In either form the carton so folded occupies very little space, and may be shipped to the packager in this form for filling and sealing.

To erect the carton further for filling, the folded carton is squared up, as on a conventional squaring machine.

One end is then closed by first folding in the inner end wall flap 5. The rear wall outer end flap 7 is then folded over, and the front wall outer end flap 6 folded over and caused to overlap at least the forward portion of the rear wall outer end flap 7. The cover front wall panel flap 18 is then folded over, followed finally by folding over the cover end wall panel 9. Heat is applied to soften the adhesive, causing the front wall outer end flap 6 to become adhesively affixed to the rear wall outer end flap 7 and also to the inner end wall flap 5 through the corner recess 19. The adhesive panel 10 which now overlaps both the front wall outer end flap and rear wall outer end flap 7 at the line of engagement between the two flaps, becomes adhesively affixed to both end flaps, also securing the cover end wall panel. Flap 18 becomes affixed to cover end wall panel 9. The carton may then be filled through the end remaining open. The open end may subsequently be closed and sealed in the same manner, to form a completely sealed carton as shown in FIG. 4. Alternatively, the first carton end may be closed and/or tacked, as with glue, but not sealed, and then both carton ends sealed concurrently or simultaneously after filling of the carton.

The carton may be opened by grasping the tab 16 and removing the tear strip 15. As the cover is then lifted open, the cover end wall panels 9 are parted from the adhesive panels 10 at the severance line 11, to form the structure shown in FIG. 5. The cover may be reclosed for storing unconsumed contents.

Although the embodiment illustrated and described utilizes a tear strip for detaching the cover front wall panel from the adhesive strip, in another embodiment an adhesive strip may be utilized which is directly connected to the cover front wall panel at a severance line, and which adhesive strip is preferably affixed to the front wall 2 at spaced-apart adhesive areas. The front wall 2 may be provided with cut scores surrounding the adhesive areas to prevent the surface of the front wall from becoming torn when the adhesive strip is removed. In a further improved embodiment, transverse cuts may also be provided in the adhesive strip intermediate the adhesive areas to facilitate removal of the adhesive strip. The severance lines in any embodiment may have any desired configuration, such as spaced-apart slits, V-shaped slits, or combinations of slits and cuts of any configuration.

It is thus seen that an economical and conveniently erected and sealed carton of sufficient durability for frequent opening and reclosing is produced, which carton is produced from an integral blank so designed that adjacent blanks may be oriented for close mutual nesting to provide an appreciable saving in cost of raw material, and whereby all of the other objects of the invention are attained.

Although the invention has been described primarily as it would be practiced when a heat-sealable adhesive is carried directly on the carton blank, other types and forms of adhesive and other means of applying the adhesive to effect sealing of the carton may be employed.

Plastic (such as polyethylene) coated or wax coated paperboard, or laminated paperboard with openings for extrusion sealing, may also be employed for the cartons and carton blanks according to the invention.

It should be understood that the invention is not limited to the exact details of construction, operation, or exact materials or embodiments shown and described, as obvious modifications and equivalents will be apparent to one skilled in the art, and the invention is therefore to be limited only by the scope of the appended claims.

We claim:

1. A carton formed of an integral blank cut and scored to provide a bottom member having inner end wall flaps hingedly connected to the ends thereof, a front wall member hingedly connected to one edge of said bottom member having front wall outer end flaps hinged-

ly connected to the ends thereof, and a rear wall member hingedly connected to the other edge of said bottom member having rear wall outer end flaps hingedly connected to the ends thereof, at least the upper portion of the vertical edges of the front and rear wall outer end flaps at each end of said carton being in edge to edge engagement, a cover hingedly connected to the upper edge of said rear wall member provided with cover flaps comprising cover end wall panels and a cover front wall panel, detachable means adhesively affixing said cover front wall panel to said front wall member, and an adhesive panel detachably connected to each of said cover end wall panels and adhesively affixed to both said front wall outer end flaps and said rear wall outer end flaps at the line of engagement between the vertical edges thereof.

2. An integral blank for forming a carton cut and scored to provide a bottom member having inner end wall flaps hingedly connected to the ends thereof, a front wall member hingedly connected to one edge of said bottom member having front wall outer end flaps hingedly connected to the ends thereof, and a rear wall member hingedly connected to the other edge of said bottom member having rear wall outer end flaps hingedly connected to the ends thereof, at least the upper portion of the vertical edges of the front and rear wall outer end flaps at each end of said carton being adapted to be folded into edge to edge engagement, a cover hingedly connected to the upper edge of said rear wall member provided with cover flaps comprising cover end wall panels and a cover front wall panel, detachable means adapted for adhesively affixing said cover front wall panel to said front wall member, and an adhesive panel detachably connected to each of said cover end wall panels and adapted to be adhesively affixed to both said front wall outer end flaps and said rear wall outer end flaps at the line of engagement between the vertical edges thereof.

3. An integral blank for forming a carton cut and scored to provide a bottom member having inner end wall flaps hingedly connected to the ends thereof, a front wall member hingedly connected to one edge of said bottom member having front wall outer end flaps hingedly connected to the ends thereof, a rear wall member hingedly connected to the other edge of said bottom member having rear wall outer end flaps hingedly connected to the ends thereof, and a cover hingedly connected to the upper edge of said rear wall member provided with cover flaps comprising cover end wall panels and a cover front wall panel having end flaps adapted to be adhesively affixed to said cover end wall panels, said rear wall outer end flaps, said cover end wall panels, and the end flaps of said cover front wall panel being shorter than said front wall outer end flaps and said inner end wall flaps, the upper terminal corner of each rear wall outer end flap being provided with a recess so designed that when adjacent blanks are nested together in opposite

directions the edges of the rear upper corner of the inner end wall flap of one blank are nested in substantially edge-to-edge engagement with the edges of the corner recess of the rear wall outer end flap of another blank, detachable means adapted for adhesively affixing said cover front wall panel to said front wall member, and an adhesive panel at each end of said carton detachably connected to said cover end wall panels and adapted to be adhesively affixed to both said front and said rear wall outer end flaps.

- 10 4. An integral blank for forming a carton cut and scored to provide a bottom member having inner end wall flaps hingedly connected to the ends thereof, a front wall member hingedly connected to one edge of said bottom member having front wall outer end flaps hingedly connected to the ends thereof, and a cover hingedly connected to the upper edge of said rear wall member provided with cover flaps comprising cover end wall panels and a cover front wall panel having end flaps adapted to be adhesively affixed to said cover end wall panels, said rear wall outer end flaps, said cover end wall panels, and the end flaps 15 of said cover front wall panel being shorter than said front wall outer end flaps and said inner end wall flaps, the upper terminal corner of each rear wall outer end flap being provided with a rectangular recess so designed that when adjacent blanks are nested together in opposite directions the edges of the rear upper corner of the inner end wall flap of one blank are nested in edge-to-edge engagement with the edges of the corner recess of the rear wall outer end flap of another blank, said front wall outer end flaps overlapping and adapted to be adhesively affixed to said rear wall outer end flaps, detachable means adapted for adhesively affixing said cover front wall panel to said front wall member, and an adhesive panel at each end of said carton detachably connected to said cover end wall panels and adapted to be adhesively affixed to both said front and said rear wall outer end flaps.
- 20 5. The carton of claim 1, wherein said upper terminal corner of each rear wall outer end flap is provided with a recess.
